PANTY GIRDLE

Jack E. Robbins, New York, N. Y., assignor to
Poirette Corsets Inc., New York, N. Y.

Application November 19, 1946, Serial No. 710,828

1 Claim. (Cl. 2—38)

This invention relates to girdles and corsets and more particularly to a girdle of the panty type.

It is an object of this invention to provide a girdle of the kind to be more particularly described hereinafter, having slits extending along the length of the body thereof on opposite sides, at least one of the slits extending upwardly from the lower edge and side.

Another object of this invention is to provide an improved panty girdle having a slit or opening on one side thereof extending downwardly from the waist, and a slit or opening on the other side extending upwardly from the lower edge of the leg portion and interengaging fastening elements on the adjacent edges of each of said openings with a slider for engaging the interengaging elements of each opening to secure the edges in locked position.

A still further object of this invention is to provide an improved panty girdle having an opening on opposite sides thereof which extend along the outer sides of the leg of the wearer to provide for readily putting on and removing the garment, one of the openings extending upwardly from the lower edge of one leg and the other extending downwardly from the waist.

Yet another object of this invention is to provide a panty girdle of this type having an opening on one side extending upwardly from one leg and interengaging fastening elements on each side of the opening with a slider for connecting the correlated fastening elements, the opening providing in its fullest open position, a flap which may be folded to permit the toilet of the wearer without the removal of the garment.

With the above and other objects in view, my invention consists in the arrangement, combination and details of construction disclosed in the drawings and specification, and then more particularly pointed out in the appended claim.

In the drawings,

Figure 1 is a front elevation of a corset constructed according to an embodiment of this invention.

Figure 2 is a fragmentary section taken on the line 2—2 of Figure 1.

Figure 3 is a fragmentary side elevation.

Referring to the drawing, the numeral 10 designates generally a panty girdle having a body formed with a plurality of front sections, side sections and a rear section, fixed securely together. The front section 11 is formed with four panels 12 which are secured together along their adjacent side edges by stitching, two panels on

each side of the center line of the front section 11. A pair of side sections 14 on opposite sides of the girdle 10 connect the rear section 15 and the outer edges of the outer front panels 12 together. The rear section 15 is fixed to the side sections 14 along their adjacent edges, by stitching or other suitable securing means, and the side sections 14 are secured to the front section 11 half way along the length of the adjacent edges thereof.

One side of the girdle 10 is formed with a slit between the side section 14 and the outer panel 12, which extends from the waist or top edge of the girdle downwardly a distance just short of half the length of the abutting edges of the side and front sections. The opposite side of the girdle 10 is formed with a slit between the side section 14 and center section 11, which extends upwardly from the lower edge to a point just short of half the length of the adjacent edges. The rear section 15 is fastened to the center panels 12 of the front section 11 at the center thereof by a portion of the back section which extends forwardly to form the crotch of the girdle and the inner portion of leg sections 17.

For securing the edges of the slits together there is provided a plurality of correlated interengaging fastening means 18 which are carried by the opposite edges of each slit. The fastening elements 18 are moved into interengaging locked position by a slider 19 for securing the slits in closed position. The fastening elements 18 may be made of metal or other suitable material and to prevent the metal from touching the skin of a wearer there is provided an elongated flap 19 which is secured to one side of the slit and which is adapted to underlie the fastening elements 18, when the girdle is worn.

Suitable stays 20 are fixed in the girdle between adjacent sections and between the adjacent panels of the front section to provide for the shape of the girdle on the wearer. The front and rear sections may be made of suitable fabric and the side sections 14 are preferably made of elastic material to provide a snug fit and to allow for a slight variation in size.

In the use of this girdle 10, both slits may be opened when the garment is to be put on and the slits are initially secured in a closed position by correlated hook and eye members carried by adjacent sections. As shown in Figure 2, the hook member 21 is carried by the panel 12 and the eye 22 is carried by the edge of the side section 14. Closing the interengaging fastening elements 18 completes the closing of the slits and

forms a smooth, continuous connection between the adjacent panels and sections. The slit extending upwardly from the side of the girdle 10 is again adapted to be opened to provide for folding back the lower end of the side section 14 and a part of the rear section 15, whereby it will not be necessary to remove the girdle for toilet purposes.

I do not mean to confine myself to the exact details of construction herein disclosed, but claim all variations falling within the purview of the appended claim.

What I claim is:

A panty girdle comprising a front section, a rear section, elastic side sections connecting said front and rear sections, said girdle being provided with a slit on one side extending downwardly from the upper edge of said girdle between one of said side sections and said front section a distance slightly less than one-half the length of the abutting edges of said sections, and a second slit on the opposite side between said front section and the other of said side sections, said

latter slit extending upwardly from the lower edge of said girdle a distance slightly less than one-half the length of the edges of said joining sections, and releasably inter-engaging means carried by the free edges of said sections for closing said slits, said side sections being connected together by a narrow intermediate horizontal portion of said front section in the open position of said slits providing for the ready expansion of the diameter of said girdle in application and removal from a body.
